UNITED STATES PATENT OFFICE

2,641,251

ATTACHMENT FOR EXERCISING MACHINES

Emory W. Brockman, Hartsville, Pa., assignor to
 Healthomatic Corporation, Bala-Cynwyd, Pa.,
 a corporation of Pennsylvania

Application December 27, 1950, Serial No. 202,950

11 Claims. (Cl. 128—25)

1

This invention relates to new and useful improvements in attachments for exercising machines, and more particularly to attachments for exercising machines of the type and construction disclosed in United States Letters Patent for Exercising Machine No. 2,565,348, issued August 21, 1951.

The principal object of the present invention is to provide an attachment for exercising machines of the type described which, when used in conjunction with such machines, effectively provides for the exercise and stretching of the muscles in the arms of a person, and particularly the muscles which control bending of the elbow.

Another object of the invention is to provide an attachment for exercising machines of the stated type which may be readily adjusted to meet the needs of individuals with functional limitations as well as the requirements of different sizes of persons.

A further object of the invention is to provide an attachment having the foregoing features and characteristics which is of relatively simplified construction and highly efficient and effective in use.

These and other objects of the invention and the various features and details of the construction and use thereof are hereinafter fully set forth and described with reference to the accompanying drawing, in which:

Fig. 1 is a view in perspective showing an attachment made according to the present invention in cooperating association with an exercising machine of the aforesaid type and construction;

Fig. 2 is a side elevational view of the attachment; and

Fig. 3 is a fragmentary sectional view in reduced scale on line 3—3, Fig. 2.

Referring now more particularly to the drawing, an attachment made in accordance with the present invention is shown in conjunction with an exercising machine of the construction described in United States Letters Patent No. 2,565,348, aforesaid. Such a machine embodies a hollow base structure 10 including a continuous enclosing side wall portion, a relatively fixed seat 12 and a mounting means 13 which is mounted for oscillatory movement toward and away from the seat 12 and adapted for mounting thereon a handle structure (not shown).

An attachment made in accordance with the present invention comprises a base plate 15 which is adapted to rest upon the floor and un-

2

derlie the forward end portion of the machine base 10, for example, in the relation shown in Fig. 1 of the drawing. Provided on the upper surface of the base plate 15 is a plurality of suitably arranged clamping devices constructed and arranged as described in applicant's co-pending application Serial No. 202,949, filed December 27, 1950, for securing the attachment fixedly with respect to the base 10 of the exercising machine.

Secured adjacent the outer end of the base plate 15 and inclined outwardly with respect to the exercising machine is an upstanding tubular stanchion 20 that is braced by means of angularly extending elements 21, 21 which have their upper ends secured to the stanchion 20 and their lower ends secured to the base plate 15.

Telescopically received within the tubular stanchion 20 is a stud 22. The stud 22 is adjustable in the stanchion 20 and this is accomplished by providing a series of openings in the stud and a corresponding opening in the stanchion 20 for passage of a pin 23 through a selected opening in the stud 22.

Pivottally connected to the upper end of the stud 22, for example, as indicated at 24, is the lower end of a tubular rod support 25. The rod support 25 is operatively connected to the mounting means 13 of the exercising machine so that oscillatory movement of the latter is imparted to the rod support 25. To this end there is adjustably mounted on the mounting means 13 a split sleeve or collar 26 having a set screw 27 therein for securing the sleeve or collar 26 in a selected position on the means 13. Pivottally connected, as indicated at 28, to a boss 29 on the sleeve or collar 26 is one end of a shaft member 30 which has its other end portion telescopically received within one end of a tubular member 31 that is split and provided with a set screw 32 for securing the shaft and tubular members 30 and 31, respectively, in a selected telescopic relation with respect to each other. The other end of the tubular member 31 is pivottally connected as at 33 to a boss 34 on a split collar 35 which is mounted on the rod support 25 and provided with a set screw 36 for locking the collar 35 in any desired position for adjustment lengthwise along said rod support 25.

Telescopically received within the upper end 50 of the rod support 25 is the shank portion 37 of a handle bar 38 which is provided with hand grip portions 39 on its opposite ends. The shank 37 of the handle 38 is adjustable telescopically with respect to the rod support 25 and this is accomplished by providing a series of openings in

the shank portion 37 and an opening in the rod support 25 for the passage of a pin 40 through a selected one of the openings in the handle stud 37.

The attachment is used in the manner illustrated in Fig. 1 of the drawing of an exercising machine of the type referred to previously herein. By selective adjustment of the handle shank 37 in rod support 25 and of stud 22 in the stanchion 20, the attachment may be properly set according to the size of the particular person using the same. In addition, by adjustably positioning the split collar 35 longitudinally upon the support 25 the length of the arc of oscillatory movement of the handle 38 may be varied as desired over a substantial range. This is important since in cases of extreme functional limitation of the muscles, for example, in a person's elbow resulting in inability to straighten the arm at all, it is necessary to start with a very small movement of the handle 38 and then gradually increase the arc of movement of said handle as the condition improves. Also, by adjusting the telescopic connection of the members 30 and 31 with respect to each other, the position of the rod support 25 and handle 38, angularly to the right and left of the position shown in Fig. 2 of the drawing, may be varied within the limits of extension and contraction of the telescopically adjustable members 30 and 31. When the attachment has been properly adjusted for the size of the person and for the desired arc of oscillatory movement of the handle 38, as described, the person intending to use the device sits beside the attachment, as shown in Fig. 1, and places his or her hand on one of the hand grips 39 of the handle 38. The motor of the exercising machine may then be started and the resulting oscillatory movement imparted to the handle 38 of the attachment operates effectively to exercise and stretch the muscles in the person's arm.

While a particular embodiment of the invention has been illustrated and described herein it is not intended that the invention be limited to such disclosure and changes and modifications may be made within the scope of the following claims.

I claim:

1. An attachment for exercising machines having a seat and a mounting means oscillatable relative to the seat; comprising a base, a rod support, means on said base pivotally mounting said rod support for oscillatory movement, a handle member adjustably carried by said rod support, and means connected at one end to said rod support and having at its other end a mounting for connection to the handle mount of the machine to provide a driving connection from the latter to the rod support.

2. An attachment for exercising machines having a seat and a mounting means oscillatable relative to the seat; comprising a base, a rod support, means on said base pivotally mounting said rod support for oscillatory movement, a handle member adjustably carried by said rod support, and means connected at one end to said rod support and having at its other end a mounting for connection to the handle mount of the machine to provide a driving connection from the latter to the rod support, the connection of said means to the rod support being adjustable longitudinally of the latter thereby to vary the arc of oscillatory movement of said rod support.

3. An attachment for exercising machines having a seat and a mounting means oscillatable relative to the seat; comprising a base, a rod support, means on said base pivotally mounting said rod support for oscillatory movement, a handle member adjustably carried by said rod support, and an extensible-contractible connection mounted at one end on the rod support and having at its other end a mounting for connection to the handle mount of the machine to provide a driving connection from the latter to the rod support.

4. An attachment for exercising machines having a seat and a mounting means oscillatable relative to the seat; comprising a base, a rod support, means on said base pivotally mounting said rod support for oscillatory movement, a handle member adjustably carried by said rod support, and an extensible-contractible connection mounted at one end on the rod support and having at its other end a mounting for connection to the handle mount of the machine to provide a driving connection from the latter to the rod support, the connection of said means to the rod support being adjustable longitudinally of the latter thereby to vary the arc of oscillatory movement of said rod support.

5. An attachment for exercising machines having a seat and a mounting means oscillatable relative to the seat; comprising a base, a rod support, means on said base pivotally mounting said rod support for oscillatory movement, a handle member adjustably carried by said rod support, a member mounted on the rod support and selectively adjustable longitudinally thereof, and means connected at one end to said member having at its other end a mounting for connection to the mounting means of the machine to provide a driving connection from the latter to the rod support.

6. An attachment for exercising machines having a seat and a mounting means oscillatable relative to the seat; comprising a base, a stanchion on said base inclined outwardly thereof, a stud mounted in the upper end of said stanchion and adjustable axially with respect thereto, a rod support pivotally connected at its lower end to said stud, a handle member adjustably carried by said rod support, and means connected at one end to said rod support and having at its other end a mounting for connection to the mounting means of the machine to provide a driving connection from the latter to the rod support.

7. An attachment for exercising machines having a seat and a mounting means oscillatable relative to the seat; comprising a base, a stanchion on said base inclined outwardly thereof, a stud mounted in the upper end of said stanchion and adjustable axially with respect thereto, a rod support pivotally connected at its lower end to said stud, a handle member adjustably carried by said rod support, and means connected at one end to said rod support and having at its other end a mounting for connection to the mounting means of the machine to provide a driving connection from the latter to the rod support, the connection of said means to the rod support being adjustable longitudinally of the latter thereby to vary the arc of oscillatory movement of said rod support.

8. An attachment for exercising machines having a seat and a mounting means oscillatable relative to the seat; comprising a base, a stanchion on said base inclined outwardly thereof, a stud

mounted in the upper end of said stanchion and adjustable axially with respect thereto, a rod support pivotally connected at its lower end to said stud, a handle member adjustably carried by said rod support, and an extensible-contractible connection mounted at one end on the rod support and having at its other end a mounting for connection to the mounting means of the machine to provide a driving connection from the latter to the rod support.

9. An attachment for exercising machines having a seat and a mounting means oscillatable relative to the seat; comprising a base, a stanchion on said base inclined outwardly thereof, a stud mounted in the upper end of said stanchion and adjustable axially with respect thereto, a rod support pivotally connected at its lower end to said stud, a handle member adjustably carried by said rod support, and connecting means between said rod support and the mounting means of the machine to impart the oscillatory movement of the latter to the rod support, the connection of said means to the rod support being adjustable longitudinally of the latter thereby to vary the arc of oscillatory movement of said rod support.

10. An attachment for exercising machines having a seat and a mounting means oscillatable relative to the seat; comprising a base, a stanchion on said base inclined outwardly thereof, a stud mounted in the upper end of said stanchion and adjustable axially with respect thereto, a rod support pivotally connected at its lower end to said stud, a handle member adjust-

ably carried by said rod support, a member mounted on the rod support and selectively adjustable longitudinally thereof, and means connected at one end to said member having at its other end a mounting for connection to the mounting means of the machine to provide a driving connection from the latter to the rod support.

11. An attachment for exercising machines having a seat and a mounting means oscillatable relative to the seat; comprising a base, an upstanding tubular stanchion on said base inclined outwardly thereof, a stud mounted in the upper end of said stanchion and adjustable axially with respect thereto, a rod support pivotally connected at its lower end to said stud, a handle member having a shank mounted in the upper end of said rod support and adjustable axially with respect thereto, a collar mounted on said rod support and adjustable longitudinally thereon, a sleeve adapted for removable mounting on the mounting means of the machine, and an adjustable connection between said collar and sleeve to impart oscillatory movement of the machine mounting means to the said rod support.
